(57) **CLAIM**

The ornamental design for a laboratory hood with clear panels on four sides, as shown and described.

DESCRIPTION

FIG. 1 is a perspective view of a laboratory hood with clear panels on four sides according to the present invention; FIG. 2 is an elevational view of one side of the laboratory hood with clear panels on four sides according to the present invention, the other side being substantially identical thereto;

FIG. 3 is a front elevational view of the laboratory hood with clear panels on four sides according to the present invention; and,

FIG. 4 is a rear elevational view thereof.

The top and bottom of the laboratory fume hood according to the present invention are not visible during normal use.
